UNITED STATES PATENT OFFICE

WILLIAM G. SHELTON, OF ST. LOUIS, MISSOURI

HAIR WAVING CLAMP

Application filed January 21, 1931. Serial No. 510,292.

My invention relates to the hair waving art and consists in a novel protector clamp for use in connection with a heater and curling rod such, for example, as is disclosed in Patent No. 1,778,870 issued to me October 21, 1930.

In using the types of clamps now generally known to the hair waving trade, a coil of hair wrapped around the curling rod is seated against the upper surface of the clamp and directly above the opening between the jaws. Upstanding elements are provided at each end of the clamp for supporting the rod and for counteracting the tendency of the hair to straighten and pull the rod to one side. These elements are usually located on the connecting link at one end of the jaws and the locking link at the other end and frequently interfere with the operator in segmenting, winding, and wrapping the hair and applying the heaters.

The main object of my present invention is to provide a protector clamp in which an upstanding rod supporting element is necessary at one end of the device only.

Another object is to provide a more efficient and durable locking means for the clamp.

Another object is to improve the hair engaging surface of the clamping jaws to more securely grip a strand of hair.

I attain these objects and others as indicated below in the structure illustrated in the accompanying drawings in which—

Figure 1 is a vertical transverse section showing my improved clamp, assembled with a coil of hair wrapped on a curling rod, and a heater.

Figure 2 is a view of one end of the clamp showing the ratchet and pawl engagement with the curling rod.

Figure 3 is a view of the other end of the clamp.

Figure 4 is a top view of the clamp.

Figure 5 is a vertical longitudinal section taken on line 5—5 of Figure 4.

The clamp includes elongated jaw members 1 and 2 connected at one end by a link 3 which is pivotally secured to each jaw by rivets 4. Jaw 1 is formed of insulating ma-

terial, such as bakelite or hard rubber, and is, preferably, wider than jaw 2. Jaw 2 includes a channel metal strip 5 and a pad 6 of yielding material, preferably soft rubber. A felt pad 7, secured to the bottom of each jaw, 55 serves to protect the scalp of the customer from heat and as a cushion for the weight of the rod and heater. The hair engaging faces 8 and 9 of the elongated jaws are concave and convex, respectively, and are corrugated longitudinally to provide for a more secure gripping of the hair.

An upstanding rod supporting element 10 and a pawl 11 for engagement with ratchet 14 are mounted on link 3 by means of a rivet 13 which extends through jaw 1.

At the opposite end of the clamp, I provide locking means comprising a link 15, pivotally secured to jaw 2 by means of a rivet 16, and a lever 17 having a cam 18 at one end which is arranged to fit into an arcuate depression 19 cut in the corner of jaw 1. The cam surface of the locking lever bears directly against a metal insert 20 in jaw 1 which prevents the gradual wearing away of the edge of the depression 19 and the consequent decreased efficiency of the clamp.

Link 15 has ears 31 and 32 at each end for attachment to cam lever 17 and metal strip 5, respectively, and a U-shaped intermediate portion having legs 33 and 34 of different depths. In the locked position of the clamp, the lower leg 33 of the link 15 fits into a groove 35 in the end of jaw 2, and the upper leg 34, which is less deep than the lower leg, rests on top of the jaw. This construction prevents the locking link from sticking in case the parts become bent and permits easy swinging of the link into and out of the groove 35 so that the locking of the clamp may be controlled solely by cam lever 17.

The heater shown in Figure 1 includes an arcuate body portion 25, hair gripping arms or jaws 26 and 27, and manipulating handles 29. Clamping jaw 1 is provided with a longitudinal ridge or platform 21 extending from end to end thereof and having an arcuate top 22 for seating a coil of hair wrapped around the curling rod 23. Ridge 21 serves to elevate the coiled strand above the upper sur-

100

face of the clamping jaws 1 and 2 to permit the heater jaws to freely pass between the coil and the clamp and, during the curling operation, the ridge is gripped between the 5 heater jaws to assist in maintaining the assembly in alignment.

The ridge 21 has the further function that if the clamping jaws become distorted sufficiently to cause link 15 to pass over the top of 10 jaw 1, the engagement of the lower and longer leg of link 15 with the end of the ridge will indicate to the operator that the clamp is not properly locked. In the normal locked position, the upper leg of link 15 engages the end 15 of the ridge, as shown in Figure 5.

In the permanent waving operation, a strand of hair S, previously segregated, is clamped between the jaws of the protector clamp and then wound upon the curling rod 20 in the usual manner. When the coil is wound down to the clamp, the portion of rod 23 outside of the ratchet wheel 14 is seated on the arcuate top edge of upstanding support 10 and ratchet 14 is engaged by pawl 11. Further turning of the rod by handle 24 will 25 tighten the coil and pawl 11 will prevent the strand from unwinding.

I have found that by seating the coiled strand on one side of the opening between the 30 jaws instead of directly over the opening, as is the usual case with clamps now in use, the hair pulls the rod directly downward and there is practically no tendency to pull the curling rod to one side and the coil will be 35 held securely in alignment with the jaws of the clamp without the use of any supporting element on the free end thereof.

The form of my invention described is particularly adapted for use in croquinole waving, but it will be understood that the principles of the invention may be equally advantageously embodied in a clamp for use in cork screw waving, as disclosed in my co-pending application, Serial No. 481,504, filed 45 September 12, 1930. The structure may also be modified as to various other details without departing from the spirit of the invention and I contemplate the exclusive use of all such 50 variations as come within the scope of my claims.

I claim—

1. A clamp for a hair curling device including a pair of jaw members, one of said 55 members having a longitudinal depression in its upper surface for seating a coil of hair wrapped around a curling rod and the other of said members having a substantially flat upper surface for receiving a heater jaw.

60 2. A clamp for a hair curling device comprising a pair of jaw members, a link having pivotal connections with corresponding ends of said members, locking means on the other ends of said members, and curling rod supporting means comprising an upstanding ele-

ment at one end of said jaw members and a longitudinal seat in one of said members.

3. A clamp for a hair curling device including cooperating jaw structures adapted to grip a strand of hair near its roots, and 70 an element projecting from at least one of said structures and adapted to seat a coil of hair and to be gripped between the holding jaws of a heater.

4. In a hair curling device, a clamp including a pair of hair gripping jaws, a link pivoted to corresponding ends of said jaws, locking means on the other ends of said jaws, and a curling rod and an element on said link for supporting said rod, one of said jaws 75 having a longitudinal arcuate recess in alignment with said element for seating a coil of hair wrapped around said rod.

5. In a hair curling device, a clamp member including a pair of jaws having pivotal connection at one end, one of said jaws having its outer corner at the free end cut away and provided with a wear resisting insert, and locking means secured to the free end of the other jaw, said means including a link 85 and a lever pivoted to said link and having a cam at one end adapted to engage said insert during the locking movement of said lever.

6. A clamp for a hair curling device comprising a pair of jaws having pivotal connection at one end and locking means at the other, the meeting faces of said jaws being respectively concave and convex and being corrugated longitudinally to more securely grip a 90 strand of hair.

7. A clamp for a hair curling device including a pair of jaw members having pivotal connection at one end and locking means at the other, said means including a cam lever, and a U-shaped link pivoted to one of 105 said members and having one leg longer than the other, the longer leg thereof being adapted to fit into a horizontal groove in the other jaw member when said clamp is in normal locked position.

8. A clamp for a hair curling device including a pair of jaw members having pivotal connection at one end and locking means at the other, one of said jaws having a projection on its upper surface near the locking end, said means including a cam lever and a U-shaped link having a shorter and a longer leg, said legs being adapted when in the normal locked position to respectively rest on top of said jaw members and fit into a groove in their free ends, and said longer leg being adapted to engage said projection when said members become distorted to prevent the false locking of the device.

9. In a hair curling device, a clamp including a pair of jaw members, a link having pivotal connections with corresponding ends of said members, and locking means on the other ends of said jaws, a longitudinal ridge projecting from the upper face of one of said 120 125 130

jaws, a curling rod, an element on said link for supporting said rod, and a heater including hair gripping jaws adapted to extend beneath a coil of hair wrapped around said rod and to receive said ridge between them.

5 10. In a hair curling device, a clamp including a pair of jaw members having pivotal connection at one end, and a curling rod adapted to receive a coil of hair, there being
10 a ridge projecting from the upper face of one of said jaws adjacent its inner edge having an arcuate top for seating a coil of hair wrapped around said rod.

11. In a hair curling device, a hair clamp
15 including a pair of elongated jaws for gripping a strand of hair between them, a curling rod for winding the strand into an elongated roll, and means on said clamp for engaging said rod to prevent its rotation to unwind said
20 roll, one of said jaws having an element for seating said roll with one side thereof substantially directly above the hair clamping face of that jaw whereby the portion of the strand of hair from the roll to the jaw will
25 hold the roll in alignment with its seat when the roll is tightened.

In testimony whereof I hereunto affix my signature.

WILLIAM G. SHELTON.
